CLAIM

I claim the ornamental design for a stormwater drain body, as shown and described.

DESCRIPTION

FIG. 1 is a perspective view from the front and above of a stormwater drain body, showing my new design;

FIG. 2 is a perspective view from the behind and above of the stormwater drain body;

FIG. 3 is a perspective view from the behind and below of the stormwater drain body;

FIG. 4 is a top plan view of the stormwater drain body;

FIG. 5 is a bottom plan view of the stormwater drain body;

FIG. 6 is a first side elevational view of the stormwater drain body;

FIG. 7 is a second side elevational view of the stormwater drain body;

FIG. 8 is a front elevational view of the stormwater drain body; and,

FIG. 9 is a rear elevational view of the stormwater drain body.
